UNITED STATES PATENT OFFICE.

WARREN F. FRASER, OF DORCHESTER, MASSACHUSETTS, ASSIGNOR OF ONE-HALF TO ANGUS B. FRASER, OF AMHERST, CANADA.

MACHINE FOR SEPARATING, FEEDING, AND DRIVING HEADLESS POINTED PINS.

SPECIFICATION forming part of Letters Patent No. 778,484, dated December 27, 1904.

Application filed January 16, 1904. Serial No. 189,255.

To all whom it may concern:

Be it known that I, WARREN F. FRASER, a subject of the King of England, residing at Dorchester, in the county of Suffolk and State 5 of Massachusetts, have invented new and useful Improvements in Machines for Separating, Feeding, and Driving Headless Pointed Pins, of which the following is a specification.

This invention relates to machines for separating and driving headless pins which are provided upon one end thereof with a point.

The machine of this invention is particularly adapted to separating and driving pointed headless pins through the felt bushings used 15 in certain portions of piano-actions, and after driving the point through the felt bushings said machine is provided with mechanism to cut off the point of said pin.

The invention consists in an improved separator whereby headless pointed pins are taken one by one from a raceway and fed to a receptacle with the points all extending in one direction.

The invention, again, consists in an improved feed mechanism whereby the headless pointed pins contained in mass in a hopper are taken from said hopper and delivered to a raceway, from which raceway they are taken one by one by said separator and delivered to a chute. 25 Said separator delivers the pins to said chute with the points thereof extending upwardly, and the chute is so constructed that the pins are reversed, so as to be delivered to a holder with the points extending downwardly, and 30 from said holder the mechanism is constructed to drive the pins into and through material—as, for instance, a portion of a piano-action—the point of the pin projecting through the under side of said material and subsequently being cut off by a portion of the mechanism.

The invention finally consists in the combination and arrangement of parts set forth in the following specification, and particularly pointed out in the claims thereof.

Referring to the drawings, Figure 1 is a side elevation of my improved machine for separating and driving headless pointed pins. Fig. 2 is a plan view of the same. Fig. 3 is an enlarged section taken on line 3 3 of Fig. 4. Fig. 45 4 is a section, partly in elevation, taken on

line 4 4 of Fig. 1 looking toward the left in said figure. Fig. 5 is a section, partly in elevation, taken on line 5 5 of Fig. 1. Fig. 6 is a section, partly in elevation, taken on line 6 6 of Fig. 2. Fig. 7 is an enlarged section taken on line 7 7 of Fig. 6. Fig. 8 is a detail sectional elevation taken on line 8 8 of Fig. 7 looking toward the right in said figure. Fig. 9 is a diagram illustrating in development the guideway through which the pins pass in the separating device. Fig. 10 is a detail view of a pin such as the mechanism of this invention is adapted to handle.

Like numerals refer to like parts throughout the several views of the drawings. 65

In the drawings 15 is a frame of suitable construction.

16 is the main driving-shaft journaled to rotate in bearings upon said frame.

Pins 17, one of which is illustrated in detail 70 in Fig. 10, are placed in a hopper 18, fast to the frame 15. Said hopper has a bottom 19, pivoted at 20 to the frame 15 and held in position by a spring 21, Fig. 6. The pins in the hopper are agitated by two wire fingers 22, fast to a collar 23, which in turn is fast to a vertical shaft 24, journaled to rotate in the frame 15 and to which rotary motion is imparted by a bevel-gear 25, fast thereto. The bevel-gear 25 is rotated by a bevel-gear 26, meshing therewith, 75 said bevel-gear 26 being fast to a shaft 27, journaled to rotate in the frame 15, and having fast to its outer end a spur-gear 28, which meshes into an intermediate gear 29, journaled to rotate upon a stud 30, fast to the frame 15, 80 the intermediate gear 29 meshing into a gear 31, fast to a shaft 32, which is journaled to rotate in the frame 15.

The shaft 32, Fig. 5, is rotated by means of a friction-clutch 42, consisting of a disk 33, 90 keyed to said shaft, a disk 34, mounted to slide longitudinally upon said shaft, and a pulley 35 interposed between said disks loosely mounted upon the shaft 32, said disk 34 being pressed against the side of the pulley 35 by a spiral spring 36, one end of which bears against said pulley, the other end thereof bearing against a collar 37, fast to the shaft 32. The pulley 35 is rotated by a belt 38, driven by a pulley 39, formed upon the hub of a cam 40, fast to the 95 100

main driving-shaft 16. A rotary motion is imparted to the shaft 16 by a pulley 41, fast thereto.

The pins are fed out of the hopper 18 by a feed-wheel 43, fast to the shaft 32. Said feed-wheel is provided upon its periphery with transverse grooves 44, said grooves being of such size and depth as to receive, preferably, only three pins. The feed-wheel 43 is also provided with an annular groove 45 in its periphery extending entirely therearound and located midway between the two opposite faces thereof. A raceway 46, tangential to the feed-wheel 43, extends therefrom to a separating device 47. A portion 48 of the raceway 46 extends into and partly around the groove 45, terminating below the bottom of the hopper 18. The pins are taken by the feed-wheel 43, as illustrated in Fig. 6, from the hopper 18 and carried in the direction of the arrow *a*, in said figure upwardly and onto the raceway 46, beneath a cap 49, located above said raceway. The raceway 46 guides the pins 17 to the separator 47.

The separator 47 consists, preferably, of a cylindrical casing 50, in which is journaled a carrier 51, to which a rocking motion is imparted by an arm 52, fast thereto and connected by a link 53 to a lever 54, pivoted at 55 to the frame 15. A rocking motion is imparted to the lever 54 by an eccentric 56, fast to the main shaft 16 and connected by an eccentric strap 57 and rod 58 to the lever 54. In order to prevent the pins from being jammed in the separator 47, the link 53 is provided with a slot 59, through which a screw 60 projects, fast to the lever 54, a spiral tension-spring 61 being connected from the screw 60 to the link 53.

The casing 50 is provided with an inlet-passage 62, into which one end of the raceway 46 projects. Said casing is also provided with an outlet-passage 63, through which the pins pass after being separated one from the other, as hereinafter described. The carrier 51 is provided in its periphery with a groove 64, extending longitudinally thereof. Said carrier rocks in a cylindrical chamber 65, formed in the casing 50, and adjacent to the opposite ends of said carrier grooves 66 and 67 are formed in the casing 50 concentric with the carrier 51 and in line with the groove 64. The passage 63 opens into a chute 68, said chute being provided with two passages 69 and 70, which form an acute angle one with the other. The passage 70 terminates adjacent to a vertical recess 71, formed in a holder 72, said holder terminating at its upper end in a sleeve 73, which is clamped in a groove in the frame 15 by a cap 74 and screws 75.

The sleeve 73 in addition to supporting the holder 72 constitutes a bearing in which the cylindrical driver-bar 76 is adapted to slide. The driver-bar 76 is connected by a link 77 to the lever 54, from which it receives a recip-

rocatory motion, and to the lower end of said driver-bar is fastened a driver 78.

A guide-sleeve 79 is arranged to slide upon the lower end of the driver-bar 76 and is held thereon by a screw 80, which projects through a slot 81, provided in said sleeve, said screw 79 also serving to attach the driver 78 to the driver-bar 76. A spiral compression-spring 82 encircles the driver-bar 76, the upper end thereof bearing against a shoulder 83, formed upon said driver-bar, and the lower end bearing against the top of the sleeve 79. The lower end of the driver 78 projects through a hole 84, formed in the bottom of the guide-sleeve 79.

The material 85, into which the pins are to be driven, is placed upon the top of the work-table 86, and the point of the pin which projects below the material after having been driven therein, as hereinafter described, is cut off by knives 87 87, fast to slides 88 88, arranged to slide in ways 89, formed in said work-table. The slides 88 are forced away from each other by a spiral spring 90, interposed between their adjacent ends, and are moved toward one another by levers 91 92, pivoted at 93 94, respectively, to the frame 15. A rocking motion is imparted to the levers 91 92 by cams 40 and 95, respectively. In the end of each of the levers 91 and 92 is a stud 96, having screw-threaded engagement therewith, by means of which the distance of the slides apart may be varied at either extreme of the movement of said levers 91 and 92. The work-table 86 is fast to a standard 97, which projects downwardly through a bore 98, formed in the frame 15. Said standard 97 has screw-threaded engagement with an adjusting-wheel 99 and is clamped rigidly in position upon the frame 15 by clamp-screws 100 100.

The raceway 46, Fig. 2, has two sides 101 and 102, which form a guideway 103 for the pins as they pass from the feed-wheel 43 to the separator 47, and, as will be seen in Fig. 2, said sides converge as they approach said separator. The opposite side walls 104 and 105 of the inlet-passage 62 form a continuation of the guideway 103, and said side walls also converge toward one another to the periphery of the carrier 51, Fig. 7. In order to keep the pins 17 in the raceway 46 as they pass from the feed-wheel to the separator, a cover 49 is provided which extends partly across the guideway 103, is formed in a curve at its upper end to admit the pins therewith, and is cut away upon its under side near the lower end thereof to allow the pins as they approach the carrier to roll down the raceway into contact with the periphery of said carrier without being impeded by the friction of said cover. The cover 49 is held downwardly by springs 107, located in recesses 108, formed in cross-pieces 109, fast to the

sides of the raceway 46, and said cover 49 is, moreover, guided by pins 110, fast thereto and projecting upwardly therefrom through said cross-pieces.

5 The general operation of my improved machine for separating headless pointed pins is as follows: The pins 17 in the hopper 18 are taken by the feed-wheel 43, as illustrated in Fig. 6, and carried in the direction of the 10 arrow *a* in said figure upwardly and beneath the cover 49 into the guideway 103, formed between the sides 101 and 102 of the raceway 46. Said pins are prevented from passing around with the feed-wheel by the portion 48 15 of said raceway, which guides them away from the wheel at the right-hand side thereof, Fig. 6, and beneath said cover 49 down the guideway 103 until they arrive near the lower end of said raceway, when the cover being 20 cut away upon the under side thereof the last few pins upon the raceway (five in number, as indicated in Fig. 6,) roll by gravity downwardly upon the raceway and between the converging side walls 104 and 105 of the inlet-passage 62 until they enter one by one 25 the groove 64 in the rocking carrier 51. Upon the carrier being rocked the pin contained in the groove 64 is carried by said carrier forward in the direction opposite to the arrow *b*, 30 Fig. 6. Referring to Fig. 7, it will be seen that as the pin is carried forward, as hereinbefore described, by the carrier 51 if the point thereof is located at the left, Fig. 7, it will enter the groove 67, being positively forced into said 35 groove by the inclined side wall 104, and when the carrier 51 has been rotated until the pin is brought in line with the outlet-passage 63 said pin will drop downwardly first at its free or blunt end, as illustrated in Fig. 7, the point 40 extending upwardly, and will pass out of said passage 63 into the passage 69 to the position shown in dotted lines in the passage 70, Fig. 6. It will then slide by the force of gravity down said passage 70 into the recess 71, as 45 illustrated in Fig. 3. If, on the other hand, the pin enters the groove 64 in the carrier, with the point thereof extended toward the right, Fig. 7, the converging side wall 105 will force said pin toward the right and the point 50 of the pin will enter the annular groove 66. The result, however, as to feeding the pin with the pointed end extending upwardly from the carrier to the chute will be the same as in the case where the pin had the pointed end thereof 55 extended toward the left in said Fig. 7, for the free end of said pin will drop first when it is brought in line with the outlet-passage 63, and thus said pin will pass into the chute-passage 69 to the position illustrated in dotted 60 lines, Fig. 6, in the passage 70, and thence will slide down into the recess 71 in the holder 72. When the pin drops into the recess 71, it is prevented from passing downwardly therefrom by a slide 111, Fig. 3, which is held 65 toward the right, with its end projecting into

the recess 71, by a lever 112, pivoted to the holder 72 at 113 and held in the position illustrated by a spiral spring 114. Assuming the pin now to be standing in the recess 71, as illustrated in Fig. 3, the machine is so timed 70 that the driver-bar 76 moves downwardly until the lower end of the sleeve 79 comes in contact with the top of said pin. It will be noted that said sleeve has a concavity 115 in the under side thereof for the purpose of moving 75 the pin into a vertical position if it happens to be standing at an angle in the recess 71. The driver-bar 76, driver 78, and sleeve 79 descend until the bottom of said sleeve rests upon the holder 72. Upon a continued downward movement of the driver-bar the driver forces the pin through the recess 71 and into the material 85. The knives 87 are now forced toward each other by the levers 91 and 92 and the point of the pin cut off. 85

In Fig. 9 a development of the side walls 104 and 105, together with the grooves 66 and 67 formed therein, respectively, is illustrated with pins in the position they would assume when being carried through between said side 90 walls by the rotation of the carrier 51. It is evident that without departing from the spirit of my invention the carrier 51 may be made to continuously rotate instead of being rocked, as hereinbefore described, or said carrier may 95 be made a reciprocatory carrier, the broad principle of the invention being that a moving carrier provided with a groove to receive a headless pointed pin carries said pin between two converging side walls, each provided with a groove, the pointed end of the pin passing into one of said grooves according to the direction in which said pointed end is extended, and when said pin has been moved by the carrier to a point opposite the exit- 100 passage the blunt end of said pin will drop downwardly while the pointed end still remains in the groove, thus insuring a positive feed of the pins one by one, with the points all extending in the same direction. 105

Having thus described my invention, what I claim, and desire by Letters Patent to secure, is—

1. In a machine for feeding and separating pointed headless pins, a carrier, a casing therefor provided with an inlet and an outlet passage and guides for said pins, said guides provided with grooves located adjacent to opposite ends, respectively, of said carrier and adapted to receive the points of said pins. 115

2. In a machine for feeding and separating pointed headless pins a rotary carrier and a casing therefor provided with an inlet and an outlet passage, and guides provided with grooves located adjacent to opposite ends of 120 said carrier, respectively, and adapted to receive the points of said pins.

3. In a machine for feeding and separating pointed headless pins, a carrier and a casing provided with a guideway for said pins, said 130

guideway provided with an inlet-passage and having converging sides and with grooves located adjacent to opposite ends of said carrier and constructed to receive the pointed ends only of said pins.

4. In a machine for feeding and separating pointed headless pins, a casing, a carrier journaled to rotate therein and provided with a longitudinal groove in the periphery thereof adapted to receive one of said pins, said casing provided with an inlet-passage and having converging side walls and with annular grooves located adjacent to the opposite ends of said carrier and constructed to receive the pointed ends only of said pins.

5. In a machine for feeding and separating pointed headless pins, a casing, a carrier journaled to rotate therein and provided with a longitudinal groove in the periphery thereof adapted to receive one of said pins, said casing provided with an inlet-passage and having converging side walls, with annular grooves located adjacent to the opposite ends of said carrier and constructed to receive the pointed ends only of said pins, and with an outlet-passage leading downwardly from

the periphery of said rotary carrier through said casing.

6. In a machine for feeding and separating pointed headless pins, a rotary feed-wheel provided with grooves in its periphery extending transversely thereof, and with an annular groove in said periphery between the two opposite side faces thereof, and a raceway tangential to said feed-wheel, a portion 35 of said raceway extending into said annular groove.

7. In a machine for feeding and separating pointed headless pins, a hopper, a rotary feed-wheel provided with an annular groove 40 in its periphery, and a raceway tangential to said feed-wheel, a portion of said raceway extending into said annular groove, partly therearound and into said hopper.

In testimony whereof I have hereunto set 45 my hand in presence of two subscribing witnesses.

WARREN F. FRASER.
